 Bendix Aviation Corporation, South Bend, Ind.,
 a corporation of Delaware

Application June 15, 1942, Serial No. 447,104

12 Claims. (Cl. 64—25)

This invention relates to couplings and more particularly to means for connecting two rotating parts, such as parts of an internal combustion engine ignition system, so that automatic angular adjustments of said parts may be effected during rotation thereof, whereby the timing of the sparks produced by the ignition system in the engine cylinders may be automatically varied.

One of the objects of the present invention is to provide novel apparatus for mechanically coupling two rotating elements to each other while permitting of angular adjustment of one of said elements relative to the other.

Another object of the invention is to provide a novel automatic variable coupling for rotating parts which functions in accordance with the speed of rotation of said parts.

A further object is to provide novel means for automatically effecting adjustments in the timing of the ignition system of an internal combustion engine.

Still another object is to provide novel coupling means of the above character whereby two rotating parts may be automatically angularly adjusted in one direction relative to each other at one speed of rotation and in the other direction at a higher speed of rotation.

A still further object is to provide a novel, centrifugally responsive device for effecting an automatic variable connection between two rotatable parts.

Another object is to provide novel means adapted for use in the ignition system of an internal combustion engine for effecting spark advance at one engine speed and a retardation of the spark at a higher engine speed or vice versa.

Another object is to provide a novel ignition apparatus for an internal combustion engine whereby the sparks in the cylinders of the engine may be both advanced and retarded relative to the position of the pistons in said cylinders by a single, centrifugally actuated unit for coupling two rotating parts which are adapted for relative angular movement.

Another object is to provide coupling means of the above character which also functions to some extent as a flexible coupling to avoid damage which might otherwise be occasioned by sudden shocks and quick changes of speed.

The above and further objects and novel features of the invention will more fully appear from the following detailed description when the same is read in connection with the accompanying drawing. It is to be expressly understood, however, that the drawing is for the purpose of il-

lustration only and is not intended as a definition of the limits of the invention, reference for this latter purpose being had primarily to the appended claims.

5 In the drawing, wherein like reference characters refer to like parts throughout the several views,

Fig. 1 is a side elevation, partly in section and with parts broken away, showing a magneto incorporating one form of the novel coupling unit comprehended by the present invention, the section of the coupling unit being taken on line 1—1 of Fig. 2;

Fig. 2 is an end elevation looking from left to right in Fig. 1, showing only the coupling unit apart from the magneto and with portions of the springs broken away; and,

Fig. 3 is a sectional view, with parts broken away, taken substantially on line 3—3 of Fig. 2.

Only one embodiment of the invention is illustrated in the drawing, by way of example, in the form of a coupling unit adapted for use in the ignition system of an internal combustion engine. As shown, the novel coupling unit of the invention is incorporated in a magneto for the purpose of automatically varying the timing of the sparks in an ignition system relative to the positions of the pistons in the engine in which the sparks occur. The form of coupling unit shown in Figs. 1 to 3 is employed for connecting a rotating part of an engine (not shown) to the rotor shaft 10 in a magneto 11 which may be of any suitable design well-known in the art and, hence, is only partially shown. In a manner also well understood by those skilled in the art, the rotor of the magneto is drivably connected with a circuit breaker cam (not shown) which operates in timed relation to the rotor and determines the time of the occurrence of the sparks in the engine cylinders. In a structure of this character wherein the timing cam is driven by the magneto rotor, the coupling unit of the present invention is preferably located so that the rotor and the cam are affected alike by adjustments made by said unit, thereby insuring the opening of the primary circuit of the magneto coil at the most advantageous moment for efficient operation irrespective of the adjustments effected by the coupling unit.

50 In the form shown, the novel coupling means of Fig. 1, whereby shaft 10 is flexibly connected to an engine driven part for automatic, angular adjustment relative thereto, comprises two end members 12 and 13 and an intermediate force-transmitting member 14. In a manner to be more

fully described hereafter, these members are novelly mounted about shaft 10 and novel centrifugally responsive means 15 and 16 are provided for drivably connecting end members 12 and 13, respectively, to said intermediate member.

For the purposes of description, end member 12 may be considered as the driving member of the coupling since it is connected, although not necessarily, to the prime mover, which in the present instance is a rotating part of an engine on which magneto 11 is mounted. As shown, the hub portion 17 of member 12 is provided at one end thereof with external splines 18 that are adapted to engage an internally splined rotating part of the engine. A bearing sleeve 19 is fitted into driving member 12 and is loosely mounted on a smooth reduced portion of shaft 10 for free, angular movement relative thereto. An arm 20 integral with or rigidly attached to driving member 12 extends in a radial direction from the axis of rotation of shaft 10 in the plane of intermediate member 14, which is, in turn, loosely mounted on the hub 21 of end member 13 for free, angular movement relative thereto. A bearing ring 22 is preferably fitted in member 14 to engage the bearing surface of hub 21.

The centrifugally responsive means 15 provided for operatively connecting members 12 and 14 comprises a lever which is preferably fabricated from two angular plates 23, 23 and a weight 24 interposed between said plates adjacent one end thereof, said parts being secured together by any suitable means, such as screws or bolts 25. The outside plates of lever 23, 24 straddle arm 20 and member 14 and are pivotally secured to the outer end of said arm by means of a pivot pin 26. An enlarged central portion of pin 26 (Fig. 1) acts as spacing means for arms 23, 23 and is surrounded by a loose fitting bearing sleeve 26a in arm 20. In a manner to appear hereafter, a bearing pin 27 connects the ends of plates 23, 23 which straddle member 14 and slidably extends through a slot 28 in said member. As shown, said slot extends generally in a radial direction, as viewed in Fig. 2, from the axis of rotation of the coupling unit, but the same may be given a variety of contours depending upon the results desired. Suitable resilient means, such as a coil spring 29, is connected to lever 23, 24 at 30 and to driving member 12 at 31, said spring being under a predetermined tension when the above-described parts are stationary for holding said parts in the positions illustrated, with bearing pin 27 engaging the outer end of slot 28.

When the above-described parts are rotated in a counter-clockwise direction (Fig. 2) at or above a predetermined angular speed, the centrifugal force acting on the weighted end of lever 23, 24 causes the latter to pivot counter-clockwise about pivot 26 against the efforts of spring 29 and the inertia of the parts and, hence, move bearing pin 27 to the inner end of slot 28. This latter movement of pin 27 necessitates angular movement of intermediate member 14 relative to driving member 12 since pivot 26 is nearer the inner end of slot 28 than it is to the outer end of said slot. Thus, at a predetermined angular speed of member 12, the centrifugally responsive means 15 becomes effective to cause a predetermined, angular movement of end member 12 relative to intermediate member 14. For example, member 14 will be moved in a counter-clockwise direction relative to driving member 12 when the weighted end of lever 23, 24 is thrown outwardly by centrifugal force. Since member 14 is connected, in a manner to

appear hereafter, to the magneto rotor, the latter is moved ahead with respect to the engine driving member when weight 23, 24 moves outwardly and causes an advance in the timing of the sparks in the engine cylinders relative to the positions of the pistons in said cylinders.

It will be understood that by properly designing the parts above described a variety of modes of operation may be obtained. If the relative angular positions of members 12 and 14 or, in the illustrated structure, spark advance is plotted against the angular speed of member 12, the contour of the curve obtained may be greatly varied, for example, by changing the contour of slot 28, by changing the initial tension or design of spring 29, by changing the connecting points or other characteristics of the several parts so that the relationship between the increase in spring tension and the increase in effective centrifugal force, as weight 15 moves outwardly, is changed or by providing additional springs that come into operation at different positions of weight 15. The spark advance or relative movement obtained may, for example, be either gradual or abrupt or it may be obtained in a series of abrupt or gradual steps.

End member 13, which may be conveniently referred to as the driven element of the coupling unit, is drivably connected to rotor shaft 10 in the illustrated embodiment by means of splines within hub 21 that mesh with external splines 32 on said shaft. Driven member 13, in the form shown, is made up of two parts 33 and 34 rigidly connected together by rivets 35 but these parts may be integral.

Centrifugally responsive means 16 are provided for drivably connecting driven member 13 to intermediate member 14, said means being similar to but having different operating characteristics than the connecting means between members 12 and 14 heretofore described. In the form illustrated, means 16 comprises two flat arcuate plates or arms 36, 36 which extend on opposite sides of radially extending arm 34 of member 13 and are pivotally secured thereto by means including pivot pin 37. In order to insure free pivotal movement of the parts thus connected together, a bearing sleeve 38 (Fig. 3) fits into an opening in arm 34 around an enlarged central portion of pin 37, said enlarged portion serving as means for spacing the centrifugal weights 36, 36.

Arm 34 is preferably in the same radial plane as member 14 so that connecting arms 36, 36 also extend on opposite sides of said member. The ends of said arms adjacent member 14 are connected together by a pin 39 (Fig. 3) having an enlarged central portion which serves to space the arms. Surrounding the enlarged central portion of pin 39 and being free for angular movement thereon is a cylinder or tube 40 which has a loose rolling or sliding fit in an elongated slot 41 in member 14. Pin 39 and bearing sleeve 40, which thus have relatively frictionless engagement with the walls of slot 41, may be considered as a part of the centrifugally responsive means 16 which includes the arms 36, 36. The connection at pin 27 between arms 23, 23 and member 14 may be the same as the connection at pin 39 to thereby provide a relatively frictionless connection.

Roller sleeve 40 is normally held against the inner end of slot 41, as shown in Fig. 2, by suitable resilient means, such as a pair of coil springs 42, 43. The upper ends of said springs as viewed in the drawing, are secured by means of suitable adapters 44 to opposite ends of a pin 45 that ex-

tends through weights 36, 36 at a point between pivots 37 and 39, said pin being surrounded by suitable spacer sleeves 46. The other end of spring 42 is secured to an angularly extending portion 47 of member 13 while the other end of spring 43 is secured to a bar 48 which freely extends through an elongated opening 49 in member 14 and is fixed to portion 47 of member 13.

In the embodiment described above, the parts of the coupling unit are held in assembled relation by a nut 50 which is threaded onto the end of rotor shaft 10. In order to insure free, angular movement of members 12 and 14 relative to each other and to member 13, a force-transmitting washer or ring 51 is interposed between bearing sleeves 19 and hub 21 of member 13. The other end of hub 21 either engages or effectively engages a shoulder on shaft 10. Since member 13 and shaft 10 are, in effect, rigidly connected to one another, they may be considered as a single element.

When the driving and driven parts 12 and 13 are rotated in a counter-clockwise direction, as viewed in Fig. 2, at a predetermined speed, which is higher than that required to cause weight means 23, 24 to move outwardly, in the manner described above, springs 42, 43 will yield to the centrifugal forces acting on weight means 16. The free end of said weight means will then move outwardly as the speed increases until roller 40 contacts the outer end of slot 41. This movement of weight arms 36, 36 may be gradual or relatively abrupt, depending upon the design, connection and arrangement of the parts, the same as explained above in connection with centrifugally responsive means 15. The effect of the above-mentioned movement of weight means 16 is to shorten the connection between members 13 and 14, thereby causing member 13 and shaft 10 to move angularly in a clockwise direction, as viewed in Fig. 2, relative to member 14. Since during this functioning of weight means 16 there is no relative angular movement of members 12 and 14, the driven element 13 and rotor shaft 10 are effectively retarded with respect to driven member 12, thereby causing a retardation of the sparks in the ignition system served by magneto 11.

As the angular speed of the parts is reduced to or slightly below the predetermined speeds at which weight means 15 and 16 reach the outward limits of their movements, in the manner above described, springs 29 and 42, 43, respectively, return said weight means to their normal or illustrated positions, thereby reversing the relative angular movements of the parts and, hence, the advance or retardation of the spark caused by the outward movements of said weight means. Thus, an engine may, for example, be operated at one spark setting for low speeds, at an advanced spark setting for intermediate speeds and at a retarded spark setting for high speeds, the spark setting being automatically effected by the apparatus of the present invention.

There is thus provided novel coupling means for rotatable parts, such as a magneto rotor and drive shaft therefor, whereby relative angular movements of said parts in either direction may be automatically effected during rotation thereof, and whereby relative angular movements in opposite directions may be effected as the speed of rotation increases. Additionally, said coupling means are so constructed as to effect different relative angular movements of the connected parts at predetermined speeds thereof in response

to centrifugal forces. The coupling units provided may be employed in a novel manner to automatically control the spark setting of an ignition system in an infinite variety of ways for the purpose of obtaining efficient and economical operation at substantially all speeds. Furthermore, the novel coupling means provided are simple in construction and operation and are also compact and reliable.

Although only one embodiment of the invention is illustrated and described in detail, it is to be expressly understood that the same is not limited thereto. As will now be apparent to those skilled in the art, various changes, such as in the design and arrangement of parts illustrated, may be made in the illustrated embodiment of the invention without departing from the spirit and scope thereof. For a definition of the limits of the invention, reference is had primarily to the appended claims.

What is claimed is:

1. Apparatus of the class described comprising a rotatable driving member, a rotatable driven member and means drivably connecting said members whereby the latter rotate together and are adapted for limited angular movement relative to each other, said connecting means comprising an intermediate element movable angularly relative to both of said members, centrifugally responsive means pivotally mounted on one of said members, other centrifugally responsive means pivotally mounted on the other of said members, resilient means resisting movement of each of said centrifugally responsive means in response to centrifugal forces, and a pin and slot connection between each of said centrifugally responsive means and said intermediate element.

2. In apparatus of the class described, at least two rotatable members adapted for limited angular movement relative to each other, and means for drivably connecting said members including an intermediate connecting element angularly movable relative to both of said members, centrifugally responsive means connecting said element and one of said members and other centrifugally responsive means connecting said element and the other of said members, one of said centrifugally responsive means being adapted to effect relative angular movement of said members in one direction in response to centrifugal forces and the other of said centrifugally responsive means being adapted to effect relative angular movement of said members in the other direction in response to centrifugal forces.

3. Apparatus of the class described comprising a rotatable driving member, a rotatable driven member, and means for drivably connecting said members whereby the latter may have limited relative angular movement, said connecting means comprising centrifugally responsive means for effecting relative angular movement of said members in one direction in response to centrifugal forces and other centrifugally responsive means for effecting relative angular movement of said members in the other direction in response to centrifugal forces, the major portions of both of said centrifugally responsive means being mounted to rotate in approximately the same path.

4. In apparatus of the class described, a rotatable driving member, a driven member mounted for rotation with an angular movement relative to said driving member, each of said mem-

bers having a radially extending arm portion, said arm portions being positioned to rotate in substantially the same path, and means for operatively connecting said members including centrifugally responsive means pivotally mounted on each of said arms, and means including an intermediate member having a sliding connection with said centrifugally responsive means operatively connecting said centrifugally responsive means whereby the latter are effective to effect relative angular movement of said members in different directions at different speeds of rotation thereof in response to centrifugal forces acting on said responsive means.

5. Apparatus of the class described comprising rotatable driving means, rotatable driven means, and means for drivably connecting said driving and driven means whereby the latter may have limited angular movement relative to each other, said connecting means including first centrifugally responsive means and second centrifugally responsive means for effecting relative angular movement of said driving and driven means, said first and second centrifugally responsive means being adapted to become operative for effecting relative angular movement of said driving and driven means at different speeds as the speed of rotation of said driving and driven means increases.

6. Apparatus of the class described comprising driving and driven rotatable members adapted for angular movement relative to each other, an intermediate torque-transmitting element movable angularly relative to both of said members, said element and said members having radially extending portions adapted to rotate in substantially the same circumferential path, centrifugally responsive means operatively connecting the radially extending portions of said element and one of said members and other centrifugally responsive means operatively connecting the radially extending portions of said element and the other of said members, and resilient means for resisting movement of both of said centrifugally responsive means, said resilient means and said centrifugally responsive means being so mounted and proportioned that the latter become operative at different speeds of rotation of said members to effect relative angular movements of said members in opposite directions in response to centrifugal forces acting on said centrifugally responsive means as the speed of rotation of said members increases.

7. Apparatus of the class described comprising a rotatable driving member, a rotatable driven member fixed against axial movement relative to said driving member, means drivably connecting said members whereby the latter rotate together and are adapted for limited angular movement relative to each other, said connecting means comprising centrifugally responsive means for effecting relative angular movement of said members in different directions during different ranges of speeds of rotation as the speed of rotation increases, and at least two independent resilient means for controlling the movements of said centrifugally responsive means in response to centrifugal forces during different ranges of speeds of said members.

8. In apparatus of the class described, at least two rotatable members fixed against axial move-

ment relative to each other and adapted for limited angular movement relative to each other, means for drivably connecting said members including centrifugally responsive means rotatable with said members for first effecting relative angular movement of said members in one direction and then effecting relative angular movement of said members in the other direction as the speed of rotation of said members increases, and at least two independent resilient means for controlling the movement of said centrifugally responsive means in response to centrifugal forces during different ranges of speeds of said members.

15. Apparatus of the class described comprising at least two rotatable members adapted for limited angular movement relative to each other, and means for drivably connecting said members, including an intermediate element movable angularly relative to both of said members, centrifugally responsive means mounted on one of said members, other centrifugally responsive means mounted on the other of said members, resilient means resisting movement of each of said centrifugally responsive means in response to centrifugal forces and a sliding connection between each of said centrifugally responsive means and said intermediate element.

10. Apparatus of the class described comprising two rotatable members adapted for angular movement relative to each other, and means drivably connecting said members, including an intermediate element loosely mounted on one of said members, centrifugally responsive means connecting one of said members to said element, other centrifugally responsive means operable independently of said first-mentioned centrifugally responsive means connecting said element to the other of said members and resilient means resisting movement of each of the centrifugally responsive means relative to said element and members.

11. Apparatus of the class described comprising two rotatable members adapted for angular movement relative to each other, and means for drivably connecting said members, comprising an intermediate element movable angularly relative to both of said members, centrifugally responsive means connecting one of said members and said element and adapted to effect a relative angular movement thereof, other centrifugally responsive means operable independently of said first-mentioned centrifugally responsive means connecting said element and the other of said members and adapted to effect relative angular movement thereof and resilient means resisting movement of each of said centrifugally responsive means in response to centrifugal forces.

12. Apparatus of the class described comprising two rotatable members adapted for angular movement relative to each other, and means drivably connecting said members and adapted to effect angular movement of one of said members relative to the other, said connecting means comprising an intermediate element movable angularly relative to both of said members and pivotally mounted centrifugally responsive means and a pin and slot connection for operatively connecting each of said members to said element.

WALTER J. SPENGLER.
